Primary Examiner — Holly E Thurman*Assistant Examiner* — Loryn K. Leblanc(74) *Attorney, Agent, or Firm* — Egbert, McDaniel & Swartz, PLLC(57) **CLAIM**

The ornamental design for a photography stick as shown and described.

DESCRIPTION

FIG. 1 is a top perspective view of a photography stick showing my new design.

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines illustrate portions of the photography stick that form no part of the claimed design.

1 Claim, 6 Drawing Sheets(56)
